16 Claims. (Cl. 315—39)

1

This invention relates to electron discharge devices and more particularly to cathodes of magnetrons. In prior art magnetrons serious difficulties have been encountered in centering the cathode, in preventing power loss due to the capacity effect between the cathode and its adjacent filamentary heater coil, in preventing overheating of the filamentary heater coil during both manufacture and normal operation of the magnetron, and in delivering at all times the proper amount of heat to the cathode. This invention has for its primary object the provision of an improved cathode. Other objects are to overcome the above mentioned difficulties. Still other objects will become apparent to those skilled in the art as this description proceeds.

Prior art magnetrons have employed a centrally located oxide-coated cylinder heated by an adjacent filamentary heater. For best results this cylinder should be accurately positioned along the axis of the central cavity of the magnetron and difficulties in centering the cylinder have been encountered.

Our invention employs a large rigid metallic cantilever support for one end of the cathode. This large support accurately supports the cathode and overcomes the centering difficulties heretofore encountered and also serves to overcome another difficulty encountered in prior art constructions in that it conducts excess heat away from the cathode.

Since prior art magnetrons deliver considerable power, they have large filamentary heaters. Furthermore they often are called upon to deliver output currents which have sharp peaks, or are otherwise modulated at high frequency. In view of the large size of the filamentary heater and its close proximity to the cathode, there is a capacitive effect between the filamentary heater and cathode which permits high frequency power to pass from the cathode to the filamentary heater and thence to ground. The power transformer that energizes the filamentary heater does not stop this flow of current since radio frequency energy in the secondary of the transformer easily passes to the primary winding in view of the capacity between such primary and secondary. The high frequency power passing to the primary winding is fed to ground, and since the anode is grounded there is an effective loss of power.

Our invention reduces this power loss in that the filamentary heater is replaced with an electron gun positioned some distance away from the cathode. The cathode is provided with a suitable target to receive the output of the electron gun,

2

and the bombardment of this target creates enough heat to operate the cathode. By reason of this arrangement, the capacity effect tending to transfer power to the filamentary heater is reduced. Furthermore, more heat can be supplied to the cathode than heretofore since heating of the prior art cathodes was limited to the temperature that the filamentary heater could withstand. During the process of manufacture of a magnetron it is desirable to heat the cathode to temperatures higher than filamentary heaters could withstand. Such heating, during processing, is for the purpose of converting the carbonates of such metals as barium and strontium into oxides; and when a thorium oxide cathode is used it serves to outgas the cathode member. At times, during operation of the magnetron as a radio frequency oscillator, back-bombardment of the cathode tends to overheat it and destroy or distort the filamentary heater. With our arrangement, the filamentary heater of the electron gun is not subjected to the high temperature of the cathode, and hence there is no damage to our device during back-bombardment of the cathode or during processing of the cathode.

The electron gun referred to above as one feature of our invention, is, together with its associated target, located in a separate evacuated envelope from the one surrounding the cathode. This prevents "poisoning" of the gun-electrode during outgassing of the magnetron.

In the drawings:

Figure 1 is a longitudinal sectional view of a magnetron embodying certain features of the invention; and

Figure 2 is a circuit diagram showing the electrical connections of certain parts of the magnetron to external current sources.

Figure 3 illustrates the principle of operation of one type of magnetron to which the invention may be applied.

In Figure 3, which illustrates one form of magnetron to which our invention may be applied, the anode block 10 has a plurality of resonator cavities 38 disposed around and opening into a main central cavity 39. The cathode cylinder 11 is in the center of the main cavity, and magnetic flux is applied parallel with and along the axis of the cathode. Electrons leaving the cathode toward the positively charged anode are deflected from a radial path to a curvilinear path by reason of the magnetic flux. As the electrons curve and graze the pole pieces 40 which separate the resonator cavities, they become bunched and set up oscillations in the resonator cavities. Power

may be extracted from the entire system by a wave guide or other coupling associated with one resonator cavity 38. Magnetrons of this type are now well known and are more fully disclosed in the co-pending application of John T. Randall and Henry A. H. Boot, Serial No. 407,680, filed August 20, 1941, which issued on February 20, 1951, as Patent No. 2,542,966, as well as in the co-pending application of James Sayers, Serial No. 577,067, filed February 9, 1945, which issued on March 27, 1951, as Patent No. 2,546,870.

In Figure 1, cathode member 11 is shown located in the central cavity 39. A copper shell 12 provided with cooling fins 13 is located in contact with and surrounding the anode 10. A power output channel 14, of any conventional type, may be employed, to extract power from the magnetron. Pole pieces 15 and 16 of the main magnet of the magnetron are provided to apply a magnetic flux parallel to the axis of the cathode 11. These pole pieces are contiguous with the shell 12. A glass envelope portion 17, which is sealed at pip 18 maintains the cathode space evacuated. Another glass envelope portion 36 also serves to maintain the cathode space evacuated.

The cathode member 11 is accurately centered along the axis of the central cavity by the heavy metallic rigid support 20 which is in turn supported by the heavy copper cylinder 21. This large rigid cantilever support enables much greater accuracy than prior art cathode mounting arrangements, and has the further advantage of serving to hold the cathode in its proper position at all times, there being no warping or bending of the heavy support 20. Support 20 may be composed of any suitable metal, but is preferably either nickel or molybdenum.

During back-bombardment of the cathode during operation of the magnetron, the cathode 11 is highly heated. The heavy supporting cylinder 20 tends to conduct excess heat away from the cathode 11. The excess heat conducted away from the cathode by metallic member 20 is transferred to copper cylinder 21 where it may be dissipated by forced air or water cooling. Cylinder 20 defines a target area 29 near the cathode surface 11 for the purpose of supplying heat to the cathode. Target 29 is bombarded by electrons from electron gun 23 which has a cylindrical shield 23 to electrostatically focus the electrons upon the target 29 in the well known manner.

The electron gun 22 is located in an evacuated space distinct from the one surrounding cathode 11. The evacuated space surrounding electron gun 22 is defined by the target 29 at the left, then by the inner walls of copper cone 20, then by the inside wall of copper cylinder 21, and finally by the glass sealing member 37. The evacuated space surrounding the cathode 11 is defined at the left by glass envelope portion 17, then by the inside wall of pole piece 15, then by copper sealing member 12, then by the inner wall of pole piece 16 as well as by the outer wall of cone 20 and finally by the glass envelope portion 36 as well as by the outer wall of copper cylinder 21. By reason of the location of the cathode 11 and the electron gun 23 in separate evacuated spaces, the filament of the electron gun is not poisoned by any gases given off by the cathode 11 during processing or operation thereof.

Referring to Figure 2, a power source 28 feeds primary winding 27 of a step-down transformer, the secondary winding 26 of which supplies cur-

rent to the filamentary coil 50 of electron gun 22. In order to provide high voltage to effect bombardment of the target 29, a source 35 of high voltage direct current has its negative pole connected to gun 22 and its positive pole connected to the metallic anode 10. The anode 10 is in turn connected electrically to the target 29 through the secondary winding 32 of a pulse transformer 31 which will hereinafter be more fully described. It is obvious that the structure thus far described is a complete cathode heating arrangement for by properly adjusting the voltage on shield 23 and the voltage of source 35, the electrons can be caused to bombard the target 29 to any desired extent. During processing of the tube, the voltages can be raised so as to effect large quantities of heat. When the tube is in operation, whereby some self-heating of the cathode occurs, the voltages can be reduced or stopped altogether and the heavy metallic cone 20 relied upon to conduct excess heat away.

In Figure 2, there is shown a pulse generator 30 feeding the primary 33 of pulse transformer 31. Pulse generator 30 may be any form of modulator known to the art, but is here referred to particularly as a generator of very short pulses, each pulse being of duration of the order of a microsecond in duration. The pulse generator 30 has a repetition rate between several hundred and several thousand pulses per second, depending on the particular requirements of the system. The short duration of the pulses tends to create high frequencies which will readily pass, due to capacitive effects, between adjacent objects. With prior art magnetrons, large quantities of energy were lost due to transfer of energy by capacity from the cathode to the filamentary heater, and from that heater to ground through the capacitive effects between the primary and secondary of the filament transformer. With our construction, the filament 40 of the electron gun 22 is located at a position so removed from the cathode 11 that the capacity between the cathode 11 and the filament 40 is negligible.

It will be seen that the electromotive force of the secondary 32, during the delivery of a pulse, opposes the high voltage existing across source 35 and thereby stops the bombardment of target 29 for the duration of the pulse. This is not a disadvantage since the heavy copper member stores sufficient heat as to iron out these very slight irregularities, and moreover the time duration of the pulses is often short as compared with the spaces between pulses.

It is apparent that the invention has its greatest advantages and novelty when applied to magnetrons, but some of the features of this invention have utility in connection with other types of electron discharge devices. We desire it understood that the claims are not limited to magnetrons except as they are by their terms so limited.

We emphasise that it is important, to achieve successful operation of the electron gun heating of a cathode, that the intense magnetic field necessary for operation of the magnetron shall be symmetrical around the cathode and shall not be so disposed as to unwantedly deflect or inhibit the electron stream intended to strike the cathode or the target connected thereto. We have found that it is desirable to analyse the magnetic field around, and in particular rearwardly of, the cathode or its target, and to ad-

Just the field strength and its disposition to take care of the factors mentioned.

We claim:

1. A magnetron comprising, an anode block defining a cylindrical cavity, a cathode, and means for heating the cathode comprising a cantilever metallic support fastened to the cathode and accurately positioning the cathode in said cavity, said cantilever support constituting the only support for said cathode, and means adjacent said support for heating the cantilever support to thereby heat the cathode.

2. A magnetron comprising, an anode block defining a cavity, a cathode within said cavity, a support for the cathode in heat transfer relation therewith, and means adjacent said support for bombarding said support with electrons to thereby heat the cathode.

3. A cathode element comprising an electron emitting member, a cantilever supporting said member in good heat transfer relation with said member, and means adjacent said cantilever for bombarding said cantilever with electrons to thereby heat said electron emitting member.

4. A cathode element for electron tubes comprising an electron emitting member, a cantilever metallic support for said member in good heat transfer relation therewith, means adjacent said support for heating said support to thereby heat the emitting member, and metallic heat dissipating means of large area and in good metallic heat transfer contact with the support to dissipate excessive heat.

5. An electron discharge device comprising an evacuated envelope having a cathode therein, a metallic cantilever support extending through the envelope and constituting the sole support for said cathode, said support having a large solid cross-section to effect good heat conduction, and means located outside of said envelope for applying heat to a limited portion of said support to thereby heat the cathode by conduction of heat from said limited portion, said means constituting the sole means for initiating heating of the cathode.

6. A magnetron comprising an anode block having a central cavity, a cathode located in said cavity, a metallic heat transfer member attached to said cathode, said heat transfer member including an electron target, an electron gun aligned with said target for bombarding said target, a modulator having its negative pole connected to said cathode and its positive pole to said anode, and a high voltage power supply for the electron gun having its negative pole connected to the electron gun and the positive pole connected to said anode.

7. A magnetron comprising an anode block defining a central cylindrical cavity and a plurality of resonator cavities around the central cavity and opening into the central cavity, an oxide-coated cylindrical cathode member, means constituting the sole support for said cathode member comprising a cantilever metallic supporting member with the suspended end attached to and in good heat transfer relation with the cathode member, said supporting member positioning said cathode member within and concentric with the central cavity, magnet pole pieces on opposite sides of said anode block for establishing a magnetic field parallel to the axis of the central cavity, one of said pole pieces defining an opening through which said supporting member passes, an evacuated envelope surrounding said central cavity, said envelope in-

cluding a portion of said supporting member, another portion of said supporting member being outside said evacuated envelope and forming an electron target, an electron gun separated from said target a sufficient distance to avoid losses from capacitive effects, means connected to said target and gun for polarizing said target and gun to effect bombardment of the target with consequent heating of said cathode, and an evacuated envelope surrounding the electron gun and target.

8. A magnetron comprising an anode block defining a central cylindrical cavity and a plurality of resonator cavities around the main cavity and opening into the main cavity, magnet pole pieces adjacent opposite ends of the central cavity for setting up a field in the central cavity parallel to the axis thereof, one of said magnet poles having an opening therethrough aligned with said central cavity, a cylindrical oxide-coated cathode member, means supporting said cathode member in said central cavity and concentric therewith, said means constituting the sole support for said cathode member and consisting of a tubular member with its axis an extension of that of the cathode member, said tubular member passing through said opening in said pole piece, an evacuated envelope surrounding the central cavity and sealed to the outer wall of said tubular member, said tubular member being sealed at the first end thereof which supports the cathode member, a sealing member at the second end of said tubular member to maintain the same evacuated, an electron gun located within the tubular member, pulsing means electrically coupled to said anode and cathode for applying pulse potentials between said cathode and anode, means electrically coupled to said electron gun and said anode for supplying high voltage potential to operate the electron gun, means adjacent said electron gun to focus the output of the electron gun upon an inner wall of said tubular member nearest the cathode member whereby to heat the cathode, and cooling means associated with the second end of said tubular member.

9. A cathode structure comprising an elongated metallic member a first end of which is an electron emitting surface, said member defining an opening throughout substantially the remainder of the elongated member, said first end sealing the first end of said member, means sealing the second end of said member, an electron gun within said opening for bombarding the inside of said member at a point near said surface to thereby heat said surface, means supporting said member only at positions remote from said first end, said supporting means constituting the sole support for said member, an anode adjacent said cathode, and an envelope surrounding said cathode and anode, said envelope being sealed around the outer wall of said tubular member.

10. A magnetron as defined in claim 1 including a first evacuated envelope surrounding the heating means and the portion of said support heated thereby; and a second evacuated envelope surrounding the remainder of said support as well as surrounding the anode block and the cathode.

11. A cathode element comprising an electron emitting member, a cantilever in good heat transfer relation with said member and supporting the latter, electron bombarding means for bombarding said cantilever with electrons to thereby

heat said emitting member, said cantilever being tubular and containing the electron bombarding means therein and sealing means for rendering the interior of said cantilever airtight.

12. A magnetron comprising an anode block defining a cavity, a cathode within said cavity, a support for the cathode in heat transfer relation therewith, and an electron gun including an electron emitter for bombarding said support with electrons to thereby heat the cathode, said electron gun having its electron emitter substantially spaced from said support to thereby effect low capacity between the electron emitter and said cathode.

13. A cathode element as defined in claim 3 in which said bombarding means comprises an electron emitter substantially spaced from said support to thereby effect low capacity between the last-named electron emitter and the cathode.

14. A cathode structure comprising a unitary member of good thermal conductivity, electron emitting means on a limited portion of said member near a first end thereof, means which constitutes the sole support for said member and is attached to it remote from said first end, and means adjacent said member for heating the member between said limited portion and the second end thereof, said last-named means including a heat generator of sufficient capacity to raise the temperature of the electron emitting means to electron emission temperature.

15. A cathode element comprising an electron emitting member, a support for said member, said support being contiguous with said emitting member and in good heat transfer relation therewith, said support being composed of a material having good thermal conductivity, and means adjacent said support for bombarding said support with electrons to thereby heat said support and in turn heat said electron emitting member, said last named means including a source of electrons and means for accelerating

and directing electrons derived from said source upon said support.

16. A cathode element comprising an elongated structural member, an electron emitting surface formed upon said structural member, said structural member being composed of a material having good thermal conductivity and being in good heat transfer relation with said electron emitting surface, and means adjacent said structural member for bombarding said member with electrons to thereby heat said member and in turn heat said electron emitting surface, said last named means including a source of electrons spaced from said elongated structural member and also including means for accelerating and directing electrons derived from said source upon a portion of said structural member.
